* cited by examiner

Primary Examiner — Sheryl Lane*Assistant Examiner* — Ieisha Price(74) *Attorney, Agent, or Firm* — Fitch Even Tabin & Flannery, LLP(57) **CLAIM**

We claim the ornamental design for a medicament sprayer, as shown and described.

DESCRIPTION

FIG. 1 is a top perspective view of a medicament sprayer, showing our new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a front elevational view thereof with the sheath shifted from its position in FIG. 3.
